UNITED STATES PATENT OFFICE.

WILLIAM B. LASSCELL, OF NEW YORK, N. Y.

UNITING STRAW BRAID ON SEWING-MACHINES.

SPECIFICATION forming part of Letters Patent No. 269,432, dated December 19, 1882.

Application filed November 27, 1882. (No model.)

To all whom it may concern:

Be it known that I, WILLIAM B. LASSCELL, of New York city, in the county and State of New York, have invented a new and useful Improvement in Uniting Straw Braid on Sewing-Machines, which improvement is fully set forth in the following specification.

This invention has for its object to enable straw braids to be united on a sewing-machine of any ordinary or suitable construction without the stitches being so clearly apparent on the right side of the goods as ordinarily.

The invention relates to the uniting of that class of braid which has the straws twisted at the edge, thus leaving a depression or eye in each straw. I have discovered that by running the seam through these depressions or eyes in the outer overlapping edge of the braid that the stitches are but little apparent on the right side, the thread between the needle-punctures lying below the upper surface of the braid along the edge thereof, and being also in part concealed or embedded in the body of the straws. The distance which the said thread lies below the top surface depends upon the size of the straw and the consequent fineness of the braid. This for the reason that with coarse braid the sewing can be made relatively nearer the edge, and also because the bent ends of the straws, which form the edge of the braid, are more nearly at right angles to the flat surfaces than in finer braid. On account of the twist in the straw, whereby the fibers in the eyes or depressions referred to lie in or approximately in the line of the seam, the thread being stretched by the tension and take-up of the sewing-machine, splits the straw until it reaches the cross-fibers, and to that extent embeds itself in the straw.

In order to sew the braid in the manner indicated, the work-guide, which is carried by the presser-foot in the ordinary straw-hat sewing-machines, (see patents granted to Charles H. Willcox, August 12, 1879, No. 218,413, and September 6, 1881, No. 246,700,) is adjusted closer to the needle than heretofore, and to allow it to act in this position and to be raised and lowered while the needle is in the fabric a groove is cut in the guiding-edge of said work-guide.

In order that the invention and the means of carrying it into effect may be fully understood, the same will now be described in connection with the accompanying drawings, which form a part of this specification.

Figure 1 shows in plan the tip or top of the crown of a hat in process of formation and the presser-foot, work-guide, work-plate, and braid-guides of the sewing-machine for operating thereon, the needle and presser-foot of the sewing-machine being represented in cross (horizontal) section. Fig. 2 is an edge view of a partly-formed tip; Fig. 3, a perspective view, showing two sections of straw braid stitched together, and Fig. 4 a view showing a single straw separated from the braid.

A is the presser-foot of the sewing-machine; B, the work-guide, carried by and adjustable on said presser-foot; C, the work-plate; D D', the braid guides or guides for the entering braid carried by said work-plate, and E the needle. These parts, as shown, are constructed as described in the aforesaid patents of Willcox, except that the presser-foot is cut away to allow the work-guide to be adjusted closer to the needle, and the guiding-edge of said work-guide is grooved at a, opposite the needle, and that the work-guide is cut away underneath to the right of the dotted line z, so as to allow the part y of the entering braid to pass freely under it.

The straw braid is represented by F. Along one edge, b, are a series of depressions or eyes, c, formed by giving a half-twist to the straws as they are bent over the edge of the braid. This twist is most clearly shown in Fig. 4, and the effect will be apparent by comparing this edge b with the opposite edge, d, on which the straws are folded over without twisting. In sewing the braid the edge b, which is the overlapping outer edge, is guided by the work-guide so that the needle passes through the eyes or depressions, as shown in Fig. 1. The feed is preferably adjusted so that the needle passes through each straw.

The effect of the stitching is seen in Figs. 2 and 3. The parts e of the stitches only are visible on the right side of the article, and these lie below the upper surface of the braid. In the form of braid shown, which is very

coarse, the stitches *e* lie about midway of the edge; but they could be made higher up or lower down by sewing farther from or closer to the edge. The thread between the parts *e* is embedded in the straw, the straw being split lengthwise of the fibers, as represented in dotted lines *f*.

Instead of grooving the guiding-edge of the work-guide, the shank of the needle could be 10 cut away on the side adjacent thereto, which would allow the needle to operate in the desired proximity to the guiding-edge.

Articles of straw braid which have been sewed in the manner explained embody my 15 improvement, so that they are readily distinguishable from articles heretofore known and used. They therefore form part of my invention.

This invention is applicable to chip and 20 other braid, as well as to "straw braid," strictly so called—that is, braid made from the stalks of cereal grains.

No claim is made herein broadly to the method of uniting straw braid by running the 25 seams along the edges of the overlapping braids below the upper surface thereof, so that the thread between the needle punctures on the right side of the article is concealed or rendered less apparent, nor to an article of 30 straw braid having the layers united by sewing-machine stitches, whereof the thread between the needle-punctures on the right side of the article lies below the upper surface of the overlapping braid, along the edge there- 35 of, these broad claims being reserved to my application for Letters Patent, filed March 16,

1882, and officially numbered 55,479, of which the present application is a division and continuation.

Having now fully described my said invention and the manner of carrying the same into effect, what I claim is—

1. An article composed of straw braids having eyes or depressions along their edges, the several layers making up the article being 45 united by sewing-machine stitches, whereof the thread between the needle-punctures on the right side of the article lies below the upper surface of the overlapping braid along the edge having said eyes or depressions, substantially as described.

2. In uniting straw braids having eyes or depressions, the method of concealing or rendering less apparent the stitches on the right side of the fabric by running the seam through 55 said eyes or depressions, substantially as described.

3. The method of uniting straw braid having eyes or depressions on the edge by overlapping the braids, automatically or mechanically guiding the same, and feeding them to the sewing mechanism, and running the seam through the eyes or depressions of the upper overlapping braid and the body of the under braid, substantially as described.

In testimony whereof I have signed this specification in the presence of two subscribing witnesses.

W. B. LASSCELL.
